UNITED STATES PATENT OFFICE.

DAVID TOWNSEND SHARPLES, OF WEST CHESTER, PENNSYLVANIA, ASSIGNOR TO THE SHARPLES SEPARATOR COMPANY, OF WEST CHESTER, PENNSYLVANIA, A CORPORATION OF PENNSYLVANIA.

DRAG BUSH.

Application filed May 14, 1921. Serial No. 469,519.

To all whom it may concern:

Be it known that I, DAVID TOWNSEND SHARPLES, a citizen of the United States, residing at West Chester, in the county of 5 Chester, State of Pennsylvania, have invented certain new and useful Improvements in Drag Bushes, of which the following is a description, reference being had to the accompanying drawing and to the figures 10 of reference marked thereon.

This invention relates to steadyng bearings for preventing wabbling or other irregular motion of the shaft or spindles rotating at high speeds and in particular, to a steadyng bearing or drag bush for centrifugal bowl separators or the like.

The manner in which these drag bushes function in connection with centrifugal separator bowls is clearly disclosed in the 20

United States patent to McCormick No. 706,-088, issued August 5, 1902, and since the invention relates only to the improved construction of the bush itself, the recitation of the invention will in the main be confined to 25

the description of the improved bush. In this prior patent, as in present constructions, the drag bush surrounds the bottom end of the separator bowl from which it is slightly spaced and functions to confine the 30 lower end of the revolving bowl within narrow limits without using the bush as an actual bearing. So long as the bowl or its bottom boss is revolving truly and in place, there is no frictional contact between the 35

bowl or boss and the surrounding bush, although the surface of the bowl boss and the inner surface of the drag bush are very close to one another, approximately one-thirty second of an inch or less. If, however, the bowl is swayed from its true position by any force, the bowl bottom comes into 40 contact with the bush and to an extent is guided by it. The bush, however, is mounted in a position so that it may shift horizontally under slight friction, so that when 45

the bowl swings against it, the bush moves slightly to one side, thus making a drag on the lateral motion of the bowl but not confining it in the sense of a bearing. These 50 bushes are generally made of wood, such as hard maple, because such a surface presents little friction when the bowl occasionally touches it, and second, because it is light enough to prevent hammer action. Wooden

bushes, however, have always been a constant source of trouble, owing to their shrinking and swelling when dry or wet. Attempts have been made to prevent this objectionable expansion by first rendering these bushes water-proof by soaking them in oil or otherwise and then enclosing them in tight fitting metal casings, but the tendency of the wood was to grow smaller, for when the wood absorbed the moisture it expanded, but not being able to move outwardly, owing to the metal band, it closed inwardly, making the hole smaller. So also, when the bush dried out a little it shrank, became loose in the metal shell and the hole contracted still more in size. It has also been proposed to make these bushes of Babbitt metal, but they did not provide the ideal frictional surfaces present in the wooden bushes.

The present invention overcomes all of these difficulties by providing a wooden or fiber bush which maintains its inner circumferential dimensions although the bush is free to expand and contract under ordinary working conditions.

A further object of this invention resides in constructing a wooden or fiber drag bush which permits a circular expansion and contraction of the bush material but not a radial expansion or contraction so that the inner circumference of the bush is main- 80 tained.

Still another object of this invention resides in providing a wooden or fiber drag bush which is free to expand and contract circularly but not radially, due to one or 90 more slots or severances entirely through the annular wall of the bush and due to the restrictive influence of a metal or other ring which is non-expansile under working conditions, which metal ring permits the bush 95 material to expand circularly about the ring by reason of the severances while restraining it from radial expansion or contraction.

Still another feature of this invention resides in the simple manner in which the 100 bush is constructed and maintained assembled.

These and other objects will in part be obvious and will in part be hereinafter more fully disclosed.

Referring more particularly to the accompanying drawings:

Figure 1 is a side elevation partly in sec-

tion of my improved drag bush shown in proper position surrounding the boss on the lower end of a centrifugal bowl separator;

Fig. 2 is an enlarged sectional view of the 5 drag bush;

Fig. 3 is a plan view thereof, and

Fig. 4 is a modified form of bush.

In Figure 1 of the drawings, the improved 10 drag bush is disclosed in connection with an improved type of centrifugal bowl separator in which the outer casing 1 is mounted on a suitable supporting bracket and encloses the separator bowl 2 which is suspended freely in said casing and rotated 15 from above by suitable mechanism.

The lower end of the cylindrical bowl 2 is closed by a removable plate or plug 5 which is threaded into the lower end of the bowl, and suitable means is provided for 20 forming a tight joint connection between this plate and the bowl proper. Said plug or plate 5 is provided with an inlet opening 6. The casing 1 is formed with an opening 7 in which is placed a ferrule 8, the upper 25 end of which is turned inwardly to form a flange 9. The central opening through the flange 9 is slightly larger than the projecting end 10 of the plate 5. Located within the ferrule 8 is a drag bush 11 which is 30 slightly spaced from the projecting end 10, the separation being approximately one thirty-second of an inch. The specific construction of this drag bush will be described later. The spring 12 bears against the bush 35 11 at its upper end and at its lower end against a housing 13, provided with an extension 14 fitting the cylindrical lug 15 carried by the receptacle 16. This receptacle 16 is adapted to engage the lower end of the 40 casing 1 and is suitably secured thereto. The drag bush 11 is forced by means of the spring against the flange 9. The diameter of this drag bush is less than the inner diameter of the housing 13. It will be evident 45 from the above construction that when the lower end of the bowl wobbles or deviates from its true axis of rotation, the boss 10 which is normally spaced from the inner circumference of the drag bush, will come 50 into frictional engagement with the inner circumference of this drag bush, which engagement will cause the lateral displacement of the bush on its seat 9 against which seat it is resiliently held by means of the 55 spring 12. In this manner, the breaking action of the bush tends to center the bowl so that it may rotate smoothly about its vertical axis.

My improved form of drag bush 60 comprises a wooden or fiber ring 11, which in the preferred form of the invention is slotted preferably radially through the annular wall to form a plurality of segments 18, preferably four in number. Either before 65 or after slotting operation, the integral ring

or the cut segments are provided with concentric grooves 19 and 20 placed in the upper and lower faces of the ring. A ring 21 of metal or material which does not expand or contract when subjected to moisture, 70 is arranged in each of these grooves 19 and 20. This ring 21 has such a predetermined circumference that the segments 18 will be assembled in spaced relation, the inner circumference of the bush when thus assembled 75 being of a predetermined dimension so that the inner wall 22 of the bush will be spaced a desired distance from the outer wall of the end 10 on the lower end of the bowl, about one thirty-second of an inch. 80

In Figure 4, another type of bush is shown, wherein the ring 11' is provided with a single severance or slot 18' entirely through the annular wall. This ring is provided as before with a desired number of 85 metallic rings 21' to maintain the adjacent ends of the severed ring in spaced relation and the inner circumference of predetermined dimension.

It will be evident from the above construction that when the drag bush is subjected to expansion or contraction, the metallic ring will effectively prevent any change in dimensions of the inner circumference for the reason that the expansion will take 90 place by reason of the wood in the segments creeping circularly around the metal ring so as to take up the hiatus between the segments. In other words, the material of the ring will not expand or contract radially, 100 but is more or less free to expand or contract circularly.

Having thus described the invention, what I claim as new and desire to secure by Letters-Patent, is:—

1. A drag bush for a separator bowl or the like comprising a wooden or fiber ring having a predetermined inner circumference, said ring having at least one severance entirely through its annular wall, and means 110 preventing the radial expansion of said ring while permitting its circular expansion due to said severance.

2. A drag bush for a separator bowl or the like comprising a wooden or fiber ring having a predetermined inner circumference, said ring being composed of a plurality of normally spaced segments, and means for maintaining such inner circumference while permitting the expansion and contraction of 115 said segments.

3. A drag bush for a separator bowl or the like comprising a wooden or fiber ring composed of one or more segments, means for normally holding said segments assembled in spaced relation, said means preventing the radial expansion and contraction of such segments while permitting their 120 circular expansion and contraction.

4. A drag bush for a separator bowl or 1

- the like comprising a wooden or fiber ring having a predetermined inner circumference, provided with a concentric groove therein, and formed with at least one severance through its annular wall, a ring having a fixed circumference disposed in said groove for preventing the radial expansion or contraction of said ring while permitting its circular expansion or contraction.
5. A drag bush for a separator bowl or the like comprising a plurality of wooden or fiber segments assembled in normally spaced relation to form a ring having a predetermined inner circumference, said segments being grooved to form a registering concentric groove on the face of the assembled ring and a ring having a fixed cir-
- cumference disposed in said groove for preventing the radial expansion of said segments while permitting their circular ex- 20
6. A drag bush for a separator bowl or the like comprising a wooden or fiber ring provided with a concentric groove in each face and formed of a plurality of segments, 25 a metal ring of predetermined circumference in each groove to assemble said segments in normally spaced relation, said ring preventing the radial expansion or contraction of said segments while permitting their cir- 30

In testimony whereof, I affix my signature.

DAVID TOWNSEND SHARPLES.
